DESIGN FOR A COMBINED POKER CHIP
HOLDER AND COASTER

George W. Barlow, Aberdeen, Wash.

Application April 3, 1946, Serial No. 128,207

Term of patent 7 years

(Cl. D34—5)

To all whom it may concern:

Be it known that I, George W. Barlow, a citizen of the United States, residing at Aberdeen, in the county of Grays Harbor and State of Washington, have invented a new, original, and ornamental design for a Combined Poker Chip Holder and Coaster, of which the following is a specification, reference being had to the accompanying drawing, forming a part thereof.

In the drawing:

I claim:

The ornamental design for a combined poker chip holder and coaster, as shown and described.
GEORGE W. BARLOW.
